(57) **CLAIM**

The ornamental design for a universal battery pack, as shown and described in the Figures.

DESCRIPTION

FIG. 1 is a three-quarter perspective view of the universal battery pack attached to the mobile computing device; FIG. 2 is a perspective view of the universal battery pack in an alternate position, attached to the mobile computing device while acting as a stand for the mobile computing device; and, FIG. 3 is another perspective view of the universal battery pack in an alternate position, attached to the mobile computing device while acting as a stand for the mobile computing device.

The broken lines showing the mobile computing device are for the purpose of illustrating environmental structure, and forms no part of the claimed design.
